By his attorney

UNITED STATES PATENT OFFICE.

MAHLON E. LAYNE, OF HOUSTON, TEXAS.

SUSPENSION MEANS FOR PUMPING APPARATUS.

Application filed September 5, 1922. Serial No. 586,186.

To all whom it may concern:

Be it known that I, MAHLON E. LAYNE, a citizen of the United States, residing at Houston, in the county of Harris and State 5 of Texas, have invented a new and useful Suspension Means for Pumping Apparatus, of which the following is a specification.

This invention relates to suspension means for pumping apparatus and is particularly directed to that type of deep-well pumping apparatus in which the entire pumping mechanism is suspended upon a support at the well surface.

An object of the invention is to provide 15 a suspension means by which a free vertical alignment of the pumping mechanism is permitted, while at the same time insuring an equal distribution of the load on the support regardless of variations in the co-operating elements of the support and said mechanism, and without necessitating a machining of the cooperating surfaces of said elements.

Various other objects will be more fully 20 apparent from the following description of accompanying drawings which form a part of this disclosure, and which illustrate a preferred form of embodiment of the invention.

25 Of the drawings:

Figure 1 is an elevation, partly in section, of a standard type of pumping apparatus having my improved suspension means incorporated therewith.

Fig. 2 is a plan view of the supporting member.

Fig. 3 is a section on line 3-3 of Fig. 2, and

Fig. 4 is an elevation looking at the right 40 side of Fig. 2.

Fig. 5 is an enlarged detail section on line 5-5 of Fig. 1.

Fig. 6 is a similar detail section illustrating an alternate construction.

In the drawings, a standard type of deep-well pumping mechanism is illustrated in Fig. 1, and includes a discharge casing 1 carrying near its lower end a pump unit 2 and connected at its upper end to a discharge head 3 having an opening connecting with a discharge pipe 4. The pump drive shaft 5 is incased in a shaft tubing 6 and is in this instance, driven by a vertical motor 7 supported upon the pump head 3.

A supporting member 8 rests upon a suitable foundation at the well surface and its

upper surface is provided with three circularly spaced radially disposed bosses 9 (see Figs. 2 and 3) which are radially angled inwardly and downwardly, and which provide seats for supporting the discharge head 3 and its connected mechanism. The head 3 has an annular flange 10 which has an under surface radially angled inwardly and downwardly (see Fig. 1), and which engages the bosses 9 and in this manner the discharge head 3 engages the supporting member 8 at three circularly spaced points and dependingly supports the entire pumping mechanism within the well.

By this arrangement the entire pumping mechanism is dependingly supported upon angled surfaces in a manner which will permit an automatic alignment of the mechanism in the well.

With particular reference to Fig. 2 it will be noted that by providing a three point suspension the bosses 9 are arranged out of relative diametric alignment which results in all of said bosses being at all times engaged by the angled flange 10 of the pump head 3 regardless of variations in the several bosses or in the flange 10.

With other types of cooperating surfaces which engage each other at diametrically opposite points or throughout their entire circumference such constant cooperative engagement can only be secured by accurate machining of the parts and will be immediately destroyed by a slight warping or uneven wearing of the parts or settling of foundation, but with the three point suspension means of the present invention in which the cooperating supporting surfaces are circularly arranged out of relative diametric alignment, the necessity of accurate machining or machining of any kind is eliminated and the question of warping or wear or settling of the parts need be given 100 no serious consideration, as the pumping mechanism will always center itself upon the three supporting bosses 9.

This is not only important by reason of the saving of the cost of machining, but also for the reason that where warping and wearing and settling of parts is not of major import a much lighter construction may be used, all of which contributes to an economic production of the apparatus.

In Fig. 6 is illustrated an alternate construction in which the bosses 9 are formed upon the under surface of the pump head

flange 10 instead of on the supporting member 8.

While the form of construction herein illustrated and described is well adapted for the purposes and objects of the invention, it is to be understood that the invention is not to be limited to the one form of embodiment herein disclosed for it is susceptible of embodiment in various other forms all coming within the scope of the following claims.

I claim:

1. In a device of the nature disclosed, a stationary supporting member having a plurality of bearing surfaces circularly arranged out of relative diametric alignment, and a well pumping mechanism provided with a circular radially angled bearing surface engaging the bearing surfaces of the supporting member to dependingly support said mechanism.

2. In a device of the nature disclosed, a stationary supporting member having a plurality of radially angled bearing surfaces circularly arranged out of relative diametric alignment, and a well pumping mechanism having a circular radially angled bearing surface engaging the bearing surfaces of the supporting member to dependingly support said mechanism.

3. In a device of the nature disclosed, a stationary supporting member having a plurality of bosses circularly arranged out of relative diametric alignment, and a well pumping mechanism provided with a circular radially angled bearing surface engaging said bosses to dependingly support said mechanism.

4. In a device of the nature disclosed, a stationary supporting member having a plurality of bosses angled radially and circularly arranged out of relative diametric alignment, and a well pumping mechanism

provided with a circular radially angled bearing surface engaging said bosses to dependingly support said mechanism.

5. In a device of the nature disclosed, a stationary annular supporting member having a plurality of bosses radially angled inwardly and downwardly and circularly arranged out of relative diametric alignment, and a well pumping mechanism extending through said supporting member and including a pump-head having an annular bearing surface radially angled inwardly and downwardly and engaging said bosses to dependingly support said mechanism.

6. In a device of the nature described, a stationary supporting member, and a member supported thereby, one of said members having a plurality of bearing surfaces circularly spaced out of relative diametric alignment, and the other member having a cooperating radially angled circular bearing surface engaging said spaced bearing surfaces.

7. In a pumping mechanism, the combination of a pump unit having a discharge casing connected to its upper end and extending vertically upward, a stationary supporting member supporting three circularly spaced inwardly and downwardly angled bosses, a member rigid with said discharge casing and having angled bearing surfaces engaging said bosses and dependingly supporting said pump unit.

8. In a device of the nature described, a stationary supporting member, and a member supported thereby, one of said members having three circularly spaced bosses, and the other member having a circular radially angled bearing surface engaging said bosses.

Signed at South Pasadena, California, this 26th day of August, 1922.

MAHLON E. LAYNE.
